CLAIM

The ornamental design for a holder for paint can, substantially as shown and described.

DESCRIPTION

FIG. 1 is a top and left side perspective view of a holder for paint can, showing my new design;
FIG. 2 is a rear elevational view thereof;
FIG. 3 is a front elevational view thereof;
FIG. 4 is a top plan view thereof;
FIG. 5 is a bottom plan view thereof; and
FIG. 6 is a right side elevational view thereof, the left side being a mirror image thereof.
